The ornamental design for a manifold for electromagnetic valves, as shown.

(30) **Foreign Application Priority Data**

DESCRIPTION

Oct. 7, 1999 (JP) 11-27356

FIG. 1 is a top, front, right-side perspective view of a manifold for electromagnetic valves showing my new design;

(51) LOC (7) Cl. **23-01**

FIG. 2 is a front view thereof;

(52) U.S. Cl. **D23/233**

FIG. 3 is a rear view thereof;

(58) Field of Search D23/233-237,

FIG. 4 is a top plan view thereof;

D23/244, 245; 137/884, 625.64, 596.13,

FIG. 5 is a bottom plan view thereof;

596.16

FIG. 6 is a left side view thereof; and,

FIG. 7 is a right side view thereof.
